UNITED STATES PATENT OFFICE.

STEPHEN BRAMBACH, OF NEW YORK, N. Y.

DESIGN FOR A PIANO-CASE.

SPECIFICATION forming part of Design No. 25,198, dated February 25, 1896.

Application filed January 22, 1896. Serial No. 576,468. Term of patent 7 years.

To all whom it may concern:

Be it known that I, STEPHEN BRAMBACH, of New York city, New York, have invented and produced a new and original Design for 5 Piano-Cases, of which the following is a specification, reference being had to the accompanying drawing, which represents a rear perspective view of the same.

This invention relates to that class of piano-cases known as "open-back" cases, and the 10 leading feature of the design consists of a piano-case provided at its back with a square frame and with a series of vertical columns that extend from the upper to the lower tim- 15 ber of the frame.

The letter A represents a piano-case pro- 15 vided at its back with a square frame com-

posed of the upper timber, a , lower timber, a' , and upright timbers a^2 .

The opening inclosed by the frame is traversed by the shafts of a number of vertical columns B that extend from the upper timber, a , to the lower timber, a' . The columns B are provided with capitals b and bases b' , as shown. The lower edge of the timber a may 25 be arched between the capitals b , as at a^3 , to increase the effect of the design.

What I claim is—

The design for a piano-case, substantially as herein shown and described.

STEPHEN BRAMBACH.
